US00D857011S

(12) **United States Design Patent** (10) Patent No.: **US D857,011 S**
(45) Date of Patent: **** Aug. 20, 2019**

(54) **BAND CONNECTOR FOR A WATCH OR A SMART WATCH**

- (71) Applicant: **Fitbit, Inc.**, San Francisco, CA (US)
(72) Inventors: **Yu Chuan Kang**, Taipei (TW); **Derek Jenchia Loh**, San Carlos, CA (US); **Benjamin Patrick Robert Jean Riot**, San Francisco, CA (US); **Jeffrey Andrew Fisher**, Mountain View, CA (US); **Patrick James Markan**, San Francisco, CA (US); **Stephen Ronald Smilovitz**, Belmont, CA (US)
(73) Assignee: **Fitbit, Inc.**, San Francisco, CA (US)
(**) Term: **15 Years**
(21) Appl. No.: **29/676,187**
(22) Filed: **Jan. 9, 2019**

CLAIM

The ornamental design for a band connector for a watch or a smart watch, as shown and described.

DESCRIPTION

This application is related to application Ser. No. 29/635,224 filed Jan. 29, 2018, which is incorporated entirely by reference herein for all purposes.

FIG. 1 is a top plan view of a band connector for a watch or a smart watch.

FIG. 2 is a bottom plan view of FIG. 1.

FIG. 3 is a right side elevation view of FIG. 1.

FIG. 4 is a left side elevation view of FIG. 1.

FIG. 5 is a front side elevation view of FIG. 1.

FIG. 6 is a back side elevation view of FIG. 1.

FIG. 7 is a close-up side elevation view of the attachment surface of FIG. 1.

FIG. 8 is an isometric view of FIG. 7.

FIG. 9 is a cross sectional view taken along line 9-9 of FIG. 7 directionally upward.

FIG. 10 is a cross sectional view taken along line 10-10 of FIG. 7 directionally downward.

FIG. 11 is a cross sectional view taken along line 11-11 of FIG. 7.

FIG. 12 is a top, right side isometric view of a pair of band connectors for a watch or a smart watch exploded off the body of a watch.

FIG. 13 is a right side elevation view of FIG. 12.

FIG. 14 is a left side elevation view of FIG. 12.

FIG. 15 front side elevation view of FIG. 12, with band connectors displaced sideways for visibility.

FIG. 16 is a back side elevation view of FIG. 15.

FIG. 17 is a top plan view of FIG. 15.

FIG. 18 is a bottom plan view of FIG. 15.

FIG. 19 is a bottom, left side isometric view of FIG. 15.

FIG. 20 is a front isometric view of one of the band connector of FIG. 12.

FIG. 21 is a front elevation view of FIG. 20.

FIG. 22 is a back side elevation view of FIG. 20.

FIG. 23 is a left side elevation view of FIG. 20.

FIG. 24 is a right side elevation view of FIG. 20.

FIG. 25 is a top plan view of FIG. 20.

FIG. 26 is a bottom plan view of FIG. 20.

FIG. 27 is a front bottom isometric view of FIG. 20.

FIG. 28 is a cross section taken along line 28-28 of FIG. 20 directionally upward.

FIG. 29 is a cross section taken along line 29-29 of FIG. 9 directionally downward; and,

FIG. 30 is a cross section taken along line 30-30 of FIG. 9. The features shown in broken lines in the drawing depict environmental subject matter only, and form no part of the claimed design. The dash dot dash lines represent unclaimed borders.
